DESIGN FOR A SPINNING BIRD'S WING TOY

Howard B. Hanes, Fort Dodge, Iowa

Application August 26, 1946, Serial No. 132,841

Term of patent 3½ years

(Cl. D34—15)

To all whom it may concern:

Be it known that I, Howard B. Hanes, a citizen of the United States, residing at Fort Dodge, in the county of Webster and State of Iowa, have invented a new, original, and ornamental Design for Spinning Bird's Wing Toy, of which the following is a specification, reference being had to the accompanying drawing, forming part thereof.

Figure 1 is a front view of the spinning bird's wing toy showing my new design.

Figures 2 and 3 are respectively a top plan view and a side view of the spinning bird's wing toy shown in Figure 1.

I claim:

The ornamental design for a spinning bird's wing toy, as shown.

HOWARD B. HANES.
